UNITED STATES PATENT OFFICE.

NORMAN C. NAYLOR, OF CHICAGO, ILLINOIS.

JOURNAL BOX.

Application filed March 17, 1924. Serial No. 699,648.

The invention relates to improvements in journal boxes for railway cars, its object being to simplify the means for pivotally attaching the cover to the box.

5 The invention consists in a structure such as hereinafter described, and as illustrated in the accompanying drawings, in which

Fig. 1 is an end view of a journal box embodying the invention;

10 Fig. 2 is a detail side elevation of the same;

Fig. 3 is a detail in longitudinal section of the hinge elements, the box bearing for the pintle being omitted;

15 Fig. 4 is a detail of the blank for the journal box lid; and

Fig. 5 is a sectional detail on the line 5—5 of Fig. 4, but showing a portion of the blank bent to cylindrical form to constitute a pintle bearing.

20 The invention is applicable to any form of journal box which is provided with a hinged lid. For convenience of illustration a form of box now in common use is represented at 10, and the lid thereof at 11.

25 The lid is connected with the box by means of a pintle 12 setting through an eye 13 formed on the box and eyes 14, 14 formed on the lid. In the form of construction 30 illustrated, the lid is held in closed or open position by means of a spring 15 which, however, does not enter into the present invention and may be replaced by any form of holding device.

35 According to the prevailing practice the hinge pintle is in the form of a headed bolt extending entirely through and beyond the hinge eyes and secured by means of a cotter pin or nut. This arrangement is not only 40 unduly expensive but is otherwise objectionable.

According to the present invention the pintle 12 is a simple rod either solid or tubular without head or transverse perforation 45 and of less length than the overall measurement of the two bearing eyes of the lid. Each of these eyes 14 is stamped to form, intermediate of its ends, a tongue 16 the free end of which preferably projects toward the 50 inner end of the eye. The distance between the inner ends of the two tongues 16, 16 is substantially equal to the length of the pintle 12.

In the construction shown for illustrating 55 the invention the lid 11 is a steel stamping formed from a blank, a portion of which is

illustrated in 4. While the blank is in flat form a slot 17 is punched in the portion 18 which is formed into the pintle bearing 14 to give the outline of the tongue 16. This 60 punching operation removes some of the metal, giving the slot substantial width, thus providing ample clearance to permit the inward bending of the tongue 16 after the section 18 of the blank has been given the cylindrical form, and the inner margin of the outer wall of the side portions of the slot have consequently been brought more closely to the side margins of the tongue.

65 In assembling the parts the pintle 12 is inserted within the bearing eyes 13 and 14, 14, the tongues 16, 16 are bent inwardly to the position shown in Fig. 3 as by a blow of a hammer. This brings the ends of the tongues opposite the ends of the pintle and 70 securely holds the latter in place without interfering with its freedom of axial movement.

75 Should it be desired to remove the lid from the box a tool may be inserted within 80 the end of one of the eyes 14 to bend the tongue 16 outwardly and thus permit the withdrawal of the pintle.

The invention is applicable to boxes made 85 of any metal whether pressed or cast, which is sufficiently pliable to permit the bending of the tongues 16.

The bending or inward deflection of the tongues 16 may be very slight, it being necessary only that the tongue be brought in 90 line with a portion of the pintle in order that it may form an abutment to hold it in place. Such slight bending imposes but very little strain on the metal and consequently eliminates all danger of fracture or 95 weakening.

The pintle holding means being located 100 within the bearing eye there are no protruding parts to injure the workman or his clothing.

105 The construction shown and described is at this time regarded as the most desirable form of the embodiment of the invention, but various changes may be made without departing from its scope. For example, the tongues 16 are shown as being rounded at their free ends and formed by actually cutting away some of the metal of the eye 14, and as having their free ends directed inwardly or toward the inner ends of the eyes. Any cut which will result in the production 110 of a tongue will serve, whether it does or

does not result in the removal of some of the surrounding metal. The configuration of the tongue is not of vital importance, nor is the direction in which it extends.

5 Obviously also it is not material to the practice of the invention whether the central hinge eye be formed on the box and the two cooperating eyes formed on the lid, or the reverse arrangement be followed, it being necessary only that the holding tongues be formed on the eyes within which the ends of the pintle are enclosed. Further, it would be within the scope of the invention to locate the tongue on the pintle, when its 10 form will permit, such tongue, when bent, to engage a shoulder on the eye.

It may be found in some instances advisable to use a different form of pintle securing means at one end, the deflected tongue 15 being employed to engage the other end.

I claim:

1. In a journal box, a lid having a pair

of aligned eyes for receiving a hinge pintle, the wall of each eye between the ends thereof being provided with an incision for forming a tongue, said tongues being directed toward each other and adapted to be bent into the path of said pintle for abutting the ends thereof for retaining said pintle within said eyes.

2. In combination, a journal box having an eye on its upper margin, a lid for said box, said lid having a pair of pintle bearing eyes on its upper end, the walls of said eyes being provided with integral tongues directed toward each other, a pintle extending through said eyes for hinging said lid to said box, said tongues being bent inwardly at an acute angle to the axis of said pintle and having their ends directed toward and 40 abutting the ends of said pintle for retaining the same within said eyes.

NORMAN C. NAYLOR.
